UNITED STATES PATENT OFFICE.

PAUL H. WELCKER, OF ST. PAUL, MINNESOTA, ASSIGNOR TO BROWN & BIGELOW, OF ST. PAUL, MINNESOTA, A CORPORATION OF MINNESOTA.

COLLAPSIBLE SOAP-DISH.

1,353,103.

Specification of Letters Patent. Patented Sept. 14, 1920.

Application filed May 3, 1920. Serial No. 378,429.

To all whom it may concern:

Be it known that I, PAUL H. WELCKER, a citizen of the United States, residing at St. Paul, in the county of Ramsey and State of Minnesota, have invented a new and useful Improvement in Collapsible Soap-Dishes, of which the following is a specification.

My invention relates to improvements in collapsible soap dishes, the primary object 10 of which is to provide a soap dish which will readily support a bar of soap when set up, or the entire tray of which can be easily removed at any time for cleansing or other purposes without destroying the supporting 15 parts of the holder. It is desirable to have a holder of a simple, inexpensive construction, which can be readily stamped from sheet material to form a neat appearing device without riveting or otherwise attaching 20 the soap tray portion of the holder and without departing from the neat appearance of the same.

The soap dish is formed from two pieces of material and is designed so that it can be 25 readily collapsed to be packed in a small space. This allows the holder to be readily sent through the mail or otherwise shipped, either singly or in quantities. When the soap dish is set up for use it is adapted to 30 form a rigid, substantial support for a bar of soap, the tray of which is readily removable from the supporting back for cleansing or other purposes.

The peculiar construction and arrangement 35 of parts will be clearly and more definitely set forth in the specification and claims.

In the drawings forming part of this specification:

40 Figure 1 is a perspective view of the collapsible dish set up ready for use.

Fig. 2 is a reduced end view of the same.

Fig. 3 is a plan view of the back of the soap dish.

45 Fig. 4 is a view of the soap dish in collapsed position.

In the drawings, the soap dish A is formed of two pieces of material, one forming a supporting back B, while the other piece forms 50 the soap tray C. The parts B and C are formed by stamping into the desired shape pieces of flat metal.

The back B of the soap dish A is formed with a marginal reinforcing rib 10 and openings 11 for engaging hooks or nails so as to

attach the back to a wall when it is desired. Engaging tongues 12 are formed in the back B projecting from the same, while supporting brackets 13 are cut from the body of the back B and are bent to extend at an 60 angle from the same. Reinforcing ribs 14 are formed in the brackets 13.

The soap dish or tray C is formed with a soap receiving recess 15, having a central drain opening 16, while the lower surface 65 thereof is scored along the lines 17 to form creases diverging toward the opening 16 from the corners of the tray C. The forward side and ends of the tray C are formed with a rolled edge 18, which forms a smooth 70 surface for the tray and also reinforces the same. The rear side of the tray C is formed with an upwardly projecting flange or wall 19, which is formed with a marginal reinforcing rib 20 to stiffen and strengthen the 75 same, and the upper edge 21 of the flange 19 is adapted to engage beneath the engaging tongues 12 when the tray C is attached to the back B of the soap dish.

When the back B of the soap dish is 80 stamped with a die from a single piece of material, the brackets 13 extend at an acute angle from the body of the back B. This allows the back B and the tray C to be packed or nested together, as illustrated in 85 Fig. 4, with the brackets 13 extending into the recess 15 of the soap tray, thus allowing the soap dish to be collapsed into a small, compact state.

When it is desired to set up the soap tray, 90 the brackets 13 are bent to extend perpendicular to the body of the back B and the edge 21 of the back 19 of the tray is slipped beneath the engaging tongues 12, while the brackets 13 are adapted to engage the lower 95 surface of the rolled edge 18 on the ends of the tray, as illustrated in Figs. 1 and 2. Thus when the back 19 is engaged beneath the tongues 12 and the tray rests on the brackets 13, the soap dish is set up with the 100 tray C rigidly supported to the back B so that the tray C will support a considerable weight, even when the parts B and C of the soap dish are formed from comparatively thin material. By engaging the outer, forward, longitudinal edge of the tray C, the same can be lifted upward and the edge 21 disengaged from the tongues 12. In this manner the tray C can be readily disengaged from the supporting back B so that 110

it can be cleansed, or the soap dish collapsed and packed into a compact state.

The marginal reinforcing rib 10 increases the stiffness and rigidity of the back B, 5 while the reinforcing and stiffening ribs 14 in the brackets 13 also materially stiffen and strengthen the same. This is also true of the reinforcing rib 20 for the tray C. The collapsible soap dish formed of two pieces of 10 sheet material makes a simple and very practical soap holding means, while the collapsible feature is of great importance, owing to the fact that it can be collapsed into a compact state and at any time readily 15 set up by anyone purchasing or receiving the soap dish. It is always desirable to have a soap dish which can be readily cleansed, as soap suds and other undesirable residue is bound to adhere and collect in the 20 tray C. This feature, in connection with the fact that the soap dish is made from two parts, eliminates the necessity of trying to clean several parts while the soap dish is fastened on the wall. On the other hand, 25 the soap tray of this device can be readily removed at any time and thoroughly cleansed and then again replaced ready for use.

In accordance with the patent statutes I 30 have described the principles of operation of my invention, together with the apparatus which I now consider to represent the best embodiment thereof, but I desire to have it understood that the construction 35 shown is only illustrative and that the invention can be carried out by other means and applied to uses other than those above set forth within the scope of the following claims:

40. 1. A collapsible soap dish, including a supporting back, a detachable soap tray, flange and tongue means above said tray adapted to hold the same to said back and supports cut from said back adapted to support said tray from below.
45. 2. A collapsible soap dish, including a supporting back, a soap tray, a holding flange formed along the rear edge of said tray, and engaging tongues and supporting 50 brackets formed integral with and sheared out of said back, adapted to engage said flange and tray respectively, to hold said tray rigid and detachable from said back.
55. 3. A collapsible soap dish, comprising two parts formed of sheet material, one of said

parts forming a supporting back and the other of said parts forming a soap tray, holding tongues formed integral with said back and brackets projecting from and formed integral with said back adapted to 60 support said soap tray against downward pressure, said tongues holding said tray in contact with said brackets.

4. A collapsible soap dish, comprising a back formed of thin, sheet material, a soap 65 tray formed of thin, sheet material, having a reinforced edge extending about three sides of the same, an upwardly projecting supporting flange projecting from said tray, a reinforcing rib formed in said flange, 70 flange engaging tongues formed on said back adapted to engage said tray supporting flange, tray supporting brackets formed integral with and projecting from said back and reinforcing ribs formed in said supporting 75 brackets.

5. A collapsible soap tray formed from two plates of sheet material, one of said plates forming a supporting back, the other of said plates forming a soap supporting 80 tray, means formed integral from the plate forming the back for engaging and supporting the part forming said soap tray to hold the plate forming the soap tray extending at approximately right angles to the plate 85 forming the supporting back, said supporting means on the plate forming said back extending at an angle from the plate when the same is formed to allow the parts to be nested together to be collapsed into a compact state.

6. In a collapsible soap dish, including a supporting back formed of a piece of thin, sheet material, a peripheral reinforcing rib formed in said back, a soap tray formed 95 from a piece of sheet material, an upwardly supporting flange formed on said tray, a marginal reinforcing rib formed in said flange, tongues formed integral with and projecting from said back adapted to engage said tray flange and brackets formed integral with said back and adapted to be bent perpendicular thereto to engage the lower edge of said soap tray when said soap tray flange is engaged by said engaging 100 tongues formed on said supporting back to detachably and collapsibly hold the tray of said soap dish to said supporting back.

PAUL H. WELCKER.
